UNSYMMETRICAL QUATERNARY AMMONIUM ALKYL SULFATES

Joseph B. Niederl, Brooklyn, N. Y., William F. Hart, Easton, Pa., and Martin E. McGreal, Sommersworth, N. H., assignors to J. B. Niederl & Associates, Inc., New York, N. Y., a corporation of New York

No Drawing. Application July 30, 1948,
Serial No. 41,728

13 Claims. (Cl. 260—247.1)

1

This invention relates to unsymmetrical quaternary ester-salts of morpholine and thiamorpholine and to the process by which they are produced.

This application carries forward work done in connection with certain of the compounds described in our Patent No. 2,380,325 relating to "Asymmetric Quaternary Ester-Salts of Morpholine," issued July 10, 1945. The present invention differs, however, in both the process as well as the types of compounds produced.

As to the process, in the present invention a more direct method is used. Instead of first preparing a reactive quaternary ammonium halide and reacting this halide with appropriate metal salts of a mono-alkyl sulfate, in the present invention a tertiary amine is reacted directly with an unsymmetrical dialkyl sulfate as follows:

Although in the present invention the alkyl radical in the anionic part of the molecule is different from any radicals in the cationic part of the molecule, all the radicals in linked to the quaternary nitrogen atom need not to be different, which is another distinguishing mark between the present invention and the patent cited above.

In addition to the improvement in process, the present invention offers two more distinct features. One of these features is the production of quaternary ammonium alkyl sulfates in which the carbon content of the anion is exactly the same as the total carbon content in the cation $Y=R_4$. Thus through the present invention the production of perfectly balanced ionics ("Equionics") has become possible. In these balanced ionics a still more perfect intramolecular synchronization of groups, possessing a priori desirable physical, chemical and physiological properties, has been realized.

The other new feature given in the present invention is the production of quaternary ammonium alkyl sulfates in which the alkyl radical in the sulfate group has a higher carbon content, than the total of carbon atoms present in the cationic part of the molecule ($Y>R_4$).

While some of the symmetrical quaternary ammonium alkyl sulfate described in our patent application Serial No. 787,468, filed November 21, 1947 ($Y<R_4$), but where the difference in carbon content between Y and R_4 is very small, approximate the behavior of the products claimed in the present invention, nevertheless these latter products differ radically from the quaternary ammonium compounds of comparable carbon content known heretofore. Usually in these latter compounds the anion is very small in com-

2

parison to the cationic portion of the molecule. The anion in such products is usually presented by ionizable chlorine while the cationic part of the molecule, in case of capillary active substances, contains at least 15 or more carbon atoms linked to the quaternary ammonium nitrogen atom.

Utilizing the reaction scheme presented in this invention, chemical compositions can be created with predetermined properties. Thus, it is possible to produce substances in which detergency is conferred upon the anion alone or upon both, the cation and the anion. The hydrophilic action of these types of compounds is then quite different from the cationic quaternary ammonium types of compounds possessing a dwarf sized anionic grouping. Thus a gradual and staggered solubility behavior can be induced in these new types of compounds claimed in the present invention. It is possible to produce substances ranging from complete water solubility to complete insolubility and from completely oil soluble substances to complete insolubility in non-polar solvents. These characteristics allow a wider range in practical and industrial applications, than with detergents which incorporate surface-activity either in the anionic part of the molecule alone (sulfonated oils, mono-alkyl sulfate salts) or only in the cationic portion of the molecule (invert soaps). Thus these new compounds are valuable as wetting, emulsifying and dispersing agents particularly in cases, where both the anionic as well as the cationic types, as well as the non-ionic detergents fail. Many of the compounds are potent germicides and fungicides.

The tertiary amines utilizable in this invention, can be of the aliphatic, aromatic, alicyclic or simple or mixed heterocyclic types. They may be plain or further substituted by hydroxyl, alkoxy and acyl groupings. The following tertiary amines have been found perfectly suitable for use in the present invention: tri-methyl amine; tri-ethyl amine; tri-ethylol amine; the tri-propyl-, the tri-butyl- and tri-amyl amines; N,N - dimethyl - amino - ethanol; N,N - diethyl-amino-ethanol; dimethyl-aniline; diethyl-, di-propyl, di-butyl, di-ethyl-anilines; N,N-dimethyl- and N,N - di - ethyl - benzyl amines; tri-benzyl amine; N,N-dimethyl- and N,N-diethyl- alpha as well as beta naphthyl amines; N,N-dimethyl-cyclo-hexyl amine; N-methyl and N-ethyl-piperidine, pyridine, quinoline, iso-quinoline; nicotine and a whole series of N-alkyl morpholines, thiamorpholines, thiamorpholine-oxides and thiamorpholine-dioxides.

Of the unsymmetrical di-alkyl sulfates the following methyl sulfates have been used in the

chemical transformation described in the present invention:

Methyl-n-butyl sulfate;
Methyl-n-amyl-;
Methyl-n-hexyl-;
Methyl-n-heptyl-;
Methyl-n-octyl-;
Methyl-n-decyl-;
Methyl-n-dodecyl-;
Methyl-n-tetradecyl-;
Methyl-n-hexadecyl-;
Methyl-n-octadecyl-sulfates.

Also the following methyl-cyclo-alkyl sulfates have been found useful:

Methyl-cyclohexyl-;
Methyl-(4-methyl) cyclohexyl-;
Methyl-(4-t-butyl) cyclohexyl-;

flask. After thoroughly mixing the contents, the flask is tightly stoppered and the reaction mixture heated on a steam bath at a temperature of 90° C. for a period of six hours. At the end of this time the reaction mixture is allowed to cool and then permitted to stand at room temperature for additional 24 hours. After this time the reaction product is washed with 50 cc. of ether at room temperature. The ether layer containing any nonreacted starting materials is allowed to separate and is then decanted off. This washing operation is once more repeated. The ether-washed reaction product, is then recrystallized from hot ethyl acetate. The product, N-ethyl-N,N,N-tri-n-amyl ammonium hexadecyl sulfate melts at 82-85° C. (uncorr.).

Using the above procedure or the method given in the succeeding example, the following additional equionics were produced:

Compounds: Sulfates	Reactants	
	Amine	Methyl-Sulfate
N,N,N-Trimethyl-N-ethyl Ammon. n-amyl.	Dimethyl-ethyl-	-n-amyl.
N,N,N-Trimethyl-N-ethylol Ammon. n-amyl.	Dimethyl-ethylol-	Do.
N,N-Dimethyl-N, N-diethyl Ammon. n-hexyl.	Di-ethyl-methyl-	n-hexyl.
N,N-Dimethyl-N, N-diethyl Ammon. cyclohexyl.	Di-ethyl-methyl-	cyclohexyl.
N,N-Dimethyl-N, N-diethylol Ammon. n-hexyl.	Di-ethylol-methyl-	n-hexyl.
N,N-Dimethyl-Morpholinium n-hexyl.	do	cyclohexyl.
N-Methyl-Pyridinium n-hexyl.	N-Methyl Morpholine.	n-hexyl.
N-Methyl-Pyridine.	Pyridine.	Do.
N-Methyl-piperidinium cyclohexyl.	do	cyclohexyl.
N,N-Dimethyl-Piperidinium n-heptyl.	N-Methyl-piperidine.	n-heptyl.
N,N, N-Tri-ethyl-N-methyl-Ammon. n-heptyl.	Tri-ethyl amine.	Do.
N,N, N-Tri-ethylol-N-methyl-Ammon. n-heptyl.	Tri-ethylol.	Do.
N-Methyl-N-ethyl-Piperidinium n-octyl.	N-Ethyl-piperidine.	n-octyl.
N,N,N-Trimethyl-N-phenyl-Ammon. n-nonyl.	Dimethylaniline.	n-nonyl.
N,N,N-Trimethyl-N-benzyl-Ammon. n-decyl.	Benzyl-dimethyl.	n-decyl.
N-Methyl-Quinolinium n-decyl.	Quinoline.	Do.
N,N-Diethyl-N-methyl-N-phenyl-Ammon. lauryl.	Diethylaniline.	lauryl.
N,N, N-Tri-iso-amyl-N-methyl Ammon. cetyl.	Tri-iso-amyl.	cetyl.
N-Methyl-N-lauryl-Piperidinium octadecyl.	N-Lauryl-piperidine.	octadecyl.
N-Methyl-N-ethyl Morpholinium n-heptyl.	N-Ethyl morpholine.	n-heptyl.

Methyl-(4-t-amyl) cyclohexyl-;
Methyl-(4-tt-octyl) cyclohexyl-sulfates.

40

Example 2.—Carbon content of anion larger than cation

Replacement of the methyl group in all the above cited methyl-alkyl sulfates by an ethyl radical, slows down the reaction, but does not preclude also the utilization of these types of mixed alkyl sulfates for the preparation of types of unsymmetrical quaternary ammonium alkyl sulfates claimed in this invention.

The process utilized has as its outstanding feature the choice of the reactants, i. e. a tertiary amine and a methyl-alkyl sulfate, which are heated together, in equimolar quantities, either in the presence or absence of a suitable solvent. The procedure involved is very much the same as described in the concomitant patent application Serial No. 787,468 and in the Journal of the American Chemical Society, vol. 70, page 618 (1948). The present invention itself as well as the pertinent reaction mechanism involved were presented before the Organic Chemistry Division at the Chicago meeting of the American Chemical Society, in April 1948. It was established, by independent syntheses that the short chain alkyl radical, in the present case, the methyl group, migrates to the nitrogen atom leaving the larger alkyl radical or cycloalkyl radical with the sulfate group, as illustrated above, and as is necessary for the production of the types of compounds claimed in this invention.

Example 1.—Equionics

One tenth mol portion of tri-n-amyl amine (B. P. 125-128°/12 mm.) is mixed under warming with one tenth mol of methyl-n-hexadecyl sulfate (M. P. 73° C.) in a round bottomed Pyrex

45

One tenth mol of N-methyl morpholine and one tenth mol of methyl-lauryl sulfate (M. P. 47-48° C.) is placed into a round bottomed Pyrex flask. A water reflux condenser is then attached to the flask and, 200 cc. of toluene added to the reaction mixture. The mixture is then refluxed for six hours. After this time, the reaction mixture is allowed to cool and is then filtered or centrifuged. The residue is then washed with 30 cc. of di-ethyl ether to remove any unreacted starting materials. After decantation of the ether layer the residue is crystallized from hot ethyl acetate. The final product, the N,N-dimethyl-morpholinium lauryl sulfate melts at 60-62° C. (uncorr.).

50

Using the above procedure or the method given in the preceding example, the following N,N-dialkyl-morpholinium alkyl sulfates were prepared:

Compound: Sulfates	Reactants	
	Morpholine	Methyl-Sulfate
N,N-Dimethyl-morpholinium myristyl.	N-Methyl-.	-myristyl.
N,N-Dimethyl-morpholinium cetyl.	do	-cetyl.
N,N-Dimethyl-morpholinium octadecyl.	do	-octadecyl.
N-Methyl-N-lauryl-morpholinium myristyl.	N-Lauryl-.	-myristyl.
N-Methyl-N-lauryl-morpholinium cetyl.	do	-cetyl.
N-Methyl-N-lauryl-morpholinium octadecyl.	do	-octadecyl.
N-Methyl-N-myristylmorpholinium cetyl.	N-Myristyl.	-myristyl.
N-Methyl-N-myristylmorpholinium octadecyl.	do	-octadecyl.
N-Methyl-N-cetyl-morpholinium octadecyl.	N-Cetyl.	Do.

75

Reacting N-alkyl-thiamorpholines, N-alkyl-thiamorpholine-oxides and N-alkyl-thiamorpholine-dioxides with methyl-cetyl sulfate and using the procedures as given in Example 1 or as described in Example 2 the following compounds were produced:

3. Morpholinium alkyl sulfates of the following formula

5

Compounds: Cetyl Sulfates	Amine
N,N-Dimethyl-thiamorpholinium	N-Methyl-thiamorpholine.
N-Methyl-N-lauryl-thiamorpholinium	N-Lauryl-thiamorpholine.
N-Methyl-N-myristyl-thiamorpholinium	N-Myristyl-thiamorpholine.
N,N-Dimethyl-thiamorpholine-oxide	N-Methyl-thiamorpholine-oxide.
N-Methyl-N-lauryl-thiamorpholine-oxide	N-Lauryl-thiamorpholine-oxide.
N-Methyl-N-myristyl-thiamorpholine-oxide	N-Myristyl-thiamorpholine-oxide.
N,N-Dimethyl-thiamorpholinium-dioxide	N-Methyl-thiamorpholine-dioxide.
N-Methyl-N-lauryl-thiamorpholinium-dioxide	N-Lauryl-thiamorpholine-dioxide.
N-Methyl-N-myristyl-thiamorpholinium-dioxide	N-Myristyl-thiamorpholine-dioxide.

Reacting various types of tertiary amines with methyl-lauryl sulfate under conditions as given in Examples 1 and 2 the following quaternary ammonium lauryl sulfates were prepared:

Compounds: Lauryl Sulphates	Tert. Amine
N,N,N,N-Tetra-methyl-ammonium	Tri-methyl-amine.
N,N,N-Tri-ethyl-N-methyl-ammonium	Tri-ethyl-amine.
N,N,N-Tri-ethylol-N-methyl-ammonium	Tri-ethylol-amine.
N-Methyl-pyridinium	Pyridine.
N-Methyl-piperidinium	Piperidine.
N-Methyl-quinolium	Quinoline.
N,N,N-Trimethyl-N-phenyl-ammonium	Dimethyl-aniline.
N,N-Di-ethyl-N-methyl-N-phenyl-ammonium	Diethyl-aniline.
N,N,N-Trimethyl- α -naphthyl-ammonium	Dimethyl- α -naphthyl amine.
N,N,N-Trimethyl- β -naphthyl-ammonium	Dimethyl- β -naphthyl amine.

What we claim is:

1. Quaternary ammonium alkyl sulfates of the following formula:

wherein R_1 and R_2 represent alkyl groups while Y is an alkyl group different from the groups R_1 and R_2 and the group

40

and wherein the number of carbon atoms present in the alkyl group Y is at least equal to the sum of the number of carbon atoms present in the alkyl groups R_1 and R_2 and the group

45

4. N,N-dimethyl morpholinium cetyl sulfate of the following formula

55

5. N,N-dimethyl morpholinium n-hexyl sulfate of the following formula

60

6. N-methyl-N-lauryl morpholinium octadecyl sulfate of the following formula

65

7. Thiamorpholinium alkyl sulfates of the following formula:

75

wherein R_1 , R_2 and Z represent organic residues of which at least two may form together with the nitrogen atom a heterocyclic nucleus, R_4 and Y represent alkyl groups, the number of carbon atoms present in the alkyl group Y being at least equal to the sum of the number of carbon atoms present in the cation.

2. Quaternary ammonium alkyl sulfates of the following formula

wherein R_1 and R_2 represent alkyl groups and Z a member of the group consisting of $-\text{O}-$, $-\text{S}-$, $-\text{SO}-$, and $-\text{SO}_2-$, while Y is an alkyl group different from the alkyl groups R_1 and R_2 as well as from the group

and wherein the number of carbon atoms present in the alkyl group Y is at least equal to the sum of the number of carbon atoms present in the alkyl groups R_1 and R_2 and the group

wherein R_1 and R_2 represent alkyl groups, while Y is an alkyl group having a number of carbon atoms at least equal to the sum of the number of carbon atoms in the alkyl groups R_1 and R_2 and the group

8. Pyridinium alkyl sulfates of the following formula:

wherein, R is an alkyl group, and Y is an alkyl group having a number of carbon atoms at least equal to the sum of the carbon atoms in the alkyl group R and in the pyridine ring.

9. A process of producing quaternary ammonium alkyl sulfates of the following formula

comprising reacting at elevated temperature a tertiary amine of the formula

with an unsymmetrical dialkyl sulfate of the formula $R_4\text{O}.\text{SO}_2.\text{OY}$, wherein R_1 , R_2 , R_3 , represent organic residues of which at least two may form together with the nitrogen atom a heterocyclic nucleus, while R_4 , and Y are alkyl groups, the number of carbon atoms present in the alkyl group Y being at least equal to the sum of the number of carbon atoms present in the tertiary amine and in the alkyl group R_4 , and Y being different from the alkyl group R_4 and from any alkyl group present in said tertiary amine.

10. A process of producing quaternary ammonium alkyl sulfates of the following formula

comprising reacting at elevated temperature a tertiary amine of the formula

with an unsymmetrical dialkyl sulfate of the formula $R_4\text{O}.\text{SO}_2.\text{OY}$, wherein R_1 , R_2 , and R_3 represent alkyl groups of which at least two may form together with the nitrogen atom a heterocyclic nucleus, while R_4 and Y are alkyl groups, the number of carbon atoms present in the alkyl group Y being at least equal to the sum of the number of carbon atoms present in the alkyl groups R_1 , R_2 , R_3 , and R_4 , and Y being different from any of the alkyl groups R_1 , R_2 , R_3 , and R_4 .

11. A process of producing quaternary ammonium sulfates of the following formula

comprising reacting at elevated temperature a tertiary amine of the following formula

wherein R_1 represents an alkyl group and Z is a member of the group consisting of $-\text{O}-$, $-\text{S}-$, $-\text{SO}-$, and $-\text{SO}_2-$, with an unsymmetrical dialkyl sulfate of the formula $R_2\text{O}.\text{SO}_2.\text{OY}$, wherein R_2 and Y are alkyl groups, the number of carbon atoms present in the alkyl group Y being at least equal to the sum of the number of carbon atoms present in the alkyl groups R_1 and R_2 and the group

and Y being different from any of the groups R_1 and R_2 and the group

12. A process of producing morpholinium alkyl sulfates of the following formula

comprising reacting at elevated temperature a morpholine compound of the formula

wherein R_1 is an alkyl group, with an unsymmetrical dialkyl sulfate of the formula

wherein R_2 and Y are alkyl groups, the number of carbon atoms present in the alkyl group Y being at least equal to the sum of the number of carbon atoms present in the alkyl groups R_1 and R_2 and the group

and Y being different from any of the groups R_1 and R_2 and the group

13. A process of producing thiamorpholinium alkyl sulfates of the following formula

comprising reacting at elevated temperature a thiamorpholine compound of the formula

wherein R_1 is an alkyl group, with an unsymmetrical dialkyl sulfate of the formula

wherein R_2 and Y are alkyl groups, the number

of carbon atoms present in the alkyl group Y being at least equal to the sum of the number of carbon atoms present in the alkyl groups R₁ and R₂ and the group
